CAN PACKAGE AND HOLDER

Robert Grantham Hughes, Toronto, Ontario, Canada, assignor to Continental Can Company, New York, N.Y., a corporation of New York

Filed Oct. 12, 1960, Ser. No. 62,288

13 Claims. (Cl. 206—65)

This invention relates in general to new and useful improvements in can holders, and more particularly to a novel can holder for holding cans of different heights.

In the past, there have been devised various types of can holders, many of which are formed of a paperboard product. However, these prior can holders have all dealt with cans of the same size. While in most instances, a number of cans of the same product are packaged together for multiple purchase distribution, there are instances where it is desired to package different products in a single package and wherein the products are packaged in containers of different sizes, for example, different heights, the package being intended for the purpose of introducing a product in conjunction with other known products, or for the purpose of making an attractive offer of related products. It is to this end that it is a primary object of the invention to provide a novel can holder which will engage cans and like beaded containers and hold the cans assembled in a package form for the distribution as a unit of a plurality of cans and wherein at least one of the cans is of a different height from the others of the cans being distributed.

Another object of the invention is to provide a novel holder for holding a plurality of beaded containers in a row for handling as a single package, the holder being formed from suitable paperboard material and serving not only as a package forming member, but also as an attractive display device for displaying the individual containers of the package.

Still another object of the invention is to provide a novel can holder which is particularly adapted for holding cans of different heights, the can holder having a unitary base on which all of the cans of the package rest, an upstanding rear wall, and individual top walls, which top walls are engaged over the upper ends of the respective ones of the cans, and the rear wall tying together the base and the top walls to securely hold the cans together as a unit in a single package.

A further object of the invention is to provide a novel package formed of three cans or other similarly beaded containers, one of which is of a different height from the others and is disposed intermediate the others, and a can holder partially wrapped around the cans and securing the cans together in a row as a single unit, the cans being interlocked with a base portion of the can holder and with individual top walls thereof wherein any twisting movement of the cans relative to each other or to the holder is resisted by the can holder and the interlock between the individual can and the can holder is increased, and the cans are removable from the can holder only through a tearing of the can holder.

Still another object of the invention is to provide a novel blank for forming a can holder for the holding of three cans, one of which cans is of a different height from the others, the blank being in the form of a paperboard product and generally rectangular in outline, the blank also being provided with suitable score lines and cuts so as to define generally a unitary base, an upstanding wall and individual top walls, the construction of the base and top walls being of a nature to provide an interlock with beaded ends of cans when the blank is shaped into a can holder and is partially wrapped around the cans to form a package.

These together with the other objects and advantages

2

which will become apparent as the following description proceeds reside in the construction and arrangement of parts as more fully set forth in the following description and appended claims and illustrated in the accompanying drawings:

In the drawings:

FIGURE 1 is a perspective view showing a package in accordance with the invention, wherein the package is formed of three cans, the central one of the cans being of a different height from the others and the cans being assembled together in a rigid unit through the use of the can holder.

FIGURE 2 is a rear perspective view of the can holder of FIGURE 1 with an endmost one of the cans being omitted and the top wall normally overlying the removed can being swung to a rearwardly disposed position in order to further illustrate the details of the can holder.

FIGURE 3 is an enlarged vertical sectional view taken along the line 3—3 of FIGURE 1, and shows the specific relationship of the can holder with respect to one of the cans, including the interlock between the beaded ends of the can and the can holder.

FIGURE 4 is an enlarged horizontal sectional view taken along the line 4—4 of FIGURE 1, and shows the alignment of the cans within the can holder and the interlocking of the flanges and rear wall of the can holder with the beads of the cans.

FIGURE 5 is a plan view on a reduced scale showing the specific details of the blank from which the can holder is formed.

Reference is now made to the drawings in detail, wherein there is illustrated in FIGURE 1 a package formed in accordance with the invention, the package being generally referred to by the numeral 10. The package 10 is formed of three cans 11, 12 and 13, and a can holder, generally referred to by the numeral 14. The cans 11, 12 and 13 are disposed in a row, with the cans 11 and 13 being disposed outermost and of the same size. The central can 12 is of the same diameter as the cans 11, 13, but is of a different height. As illustrated, the can 12 is taller than the cans 11, 13, although it is feasible in accordance with the invention that the can 12 could be shorter than the cans 11, 13.

At this time, it is pointed out that the cans 11, 12 and 13 are conventional cans, and have beaded end portions formed by the usual double seams connecting the can ends to the can body. Each can 11, 12 and 13 has a lower bead 15 and an upper bead 16, which beads are identical, and with which beads the can holder 14 interlocks in the formation of the package 10, in a manner to be described in detail hereinafter.

The specific details of the can holder 14 may be best described by first making reference to the blank of FIGURE 5, the blank being generally referred to by the numeral 17. The blank 17, for economy purposes, is a paperboard product. So, when the can holder 14 is intended to function solely for the purpose of holding the cans together in a package, it may be plain. However, normally the surface of the blank which is to be disposed outermost when the can holder 14 is formed therefrom will be provided with suitable ornamentation thereon for descriptive and/or sales appeal purposes.

The blank 17 is generally rectangular in outline and has side edges 18, 19 and a straight end 20. A first set of score lines 21, 22 extend across the blank 17 between the side edges 18, 19 adjacent to and in parallel relation to the end 20. The score lines 21, 22 are interrupted by generally C-shaped cuts 23 which are equally spaced and which correspond in position generally to the positions of the cans 11, 12 and 13 when disposed in a row. A major portion of each of the C-shaped cuts 23 lies along the line of the score line 21, and together with

the score line 21 defines a flange 24 which is relatively narrow. The free corners of the flange 24 are rounded, as at 25. The portion of the blank 19 intermediate the score lines 21, 22 defines connecting straps 26.

The portion of the blank 17 adjacent the flange 24 is in the form of a base 27. The base 27 is defined along one side thereof by the score line 22 and the cut lines 23. The opposite edge of the base 27 is in part defined by an interrupted score line 28 which, together with a closely spaced score line 29, extends transversely of the blank 17 between the side edges 18, 19. The base 27 is also in part defined by cut lines 30 which are disposed between interrupted portions of the score lines 28, 29. It is to be noted that a major portion of each cut line 30 is disposed along the line of the score lines 29. The portions of the blank 17 at the ends of the cut lines 30 and intermediate the score lines 28, 29 are in the form of straps 31. The straps 31 connect the base 27 to a rear wall 32 which is formed by a next part of the blank 17, whereas the connecting straps 26 connect the base 27 to the flange 24. It is to be noted that the base 27 has projections 33, 34 disposed along opposite sides thereof and defined by the cut lines 23, 30, respectively.

A set of interrupted score lines 35, 36 extends inwardly from the side edge 18 of the blank 17. Another set of score lines 37, 38 extends inwardly from the side edge 19 of the blank. The score lines 35 and 37 are in alignment, and the score lines 36 and 38 are in alignment. The inner portions of the score lines 35, 36, 37 and 38 terminate substantially at the third points. The score lines 35 and 36 are interrupted by an intermediate generally C-shaped cut line 39 which has a major portion thereof aligned with the score lines 35. A similar C-shaped cut line 40 is disposed intermediate portions of the score lines 37 and 38 and has the major portion thereof disposed along the score line 37.

The blank 17 has a pair of longitudinally extending straight cut lines 41, 42 which are disposed generally along the longitudinal third lines of the blank 17. The cut line 41 opens through the end of the blank 17 remote from the end 20 and terminates at its inner end at the score line 35. The cut line 42 similarly opens through the end of the blank 17 remote from the end 20 and terminates at its inner end at the score line 37.

Interrupted score lines 43, 44 extend between the cut lines 41, 42 in offset relation to the score lines 35, 37 and 36, 38. The C-shaped cut line 45 is disposed intermediate portions of the score lines 43, 44 and has a major portion thereof disposed along the score line 43.

Due to the arrangement of the score lines 35, 37 and 43 and the cut lines 39, 40 and 45, the rear wall 32 will have an irregular upper edge wherein the intermediate portion is disposed above the outer portions thereof. This differential in height in the various portions of the rear wall 32 permits the accommodation of a central can 12 which is higher than the cans 11, 13. Of course, if the center can were shorter than the outer cans, then, the relationship of the edge portions of the rear wall 32 would be reversed.

The portion of the blank 17 to the left of the cut line 41 and adjacent the rear wall 32 is in the form of a top wall 46. The wall 46 is bounded along one side by the score line 36 and the cut line 39 and along the other side thereof in part by an interrupted score line 47 which extends between the side edge 18 and the cut line 41. Associated with the score line 47 is a second score line 48. The score line 48 is also interrupted, with the interruption of the score lines 47 and 48 being in the form of a generally C-shaped cut line 49, the major portion of which cut line is disposed along the line of the score line 48. The cut line 49 also in part defines a side edge 70 of the top wall 46. The score line 48 and the central portion of the cut line 49 also define a partial flange 50.

It is to be noted that the portions of the blank 17 disposed intermediate the portions of the score lines 35, 36 are in the form of connecting straps 51 which con-

nect the top wall 46 to a corresponding portion of the rear wall 32. Also, the portions of the blank 17 intermediate the interrupted portions of the score lines 47, 48 are in the form of connecting straps 52 which connect the flange 50 to the top wall 46. The cut lines 39 and 49 also define projections 53, 54, respectively, extending from opposite sides of the top wall 46.

Score lines 55, 56 extend transversely across the blank 17 in alignment with the score lines 47 and 48, the score lines 55, 56 extending between the cut line 42 and the side edge 19. The score lines 55, 56 are interrupted by a generally C-shaped cut 57 which has a major portion thereof extending along the score line 56. The score line 38, together with the cut 40, defines one edge of a top wall 58 which corresponds to the top wall 46, while the score line 55 and the cut line 57 define a second side edge of the top wall 58. The score line 56 and the intermediate portion of the cut line 57 also defines a partial flange 59 which is connected to the top wall 58. The top wall 58 is connected to the rear wall 32 by connecting straps 60 which are disposed intermediate the portions of the score lines 37, 38. The flange 59 is connected to the top wall 58 by connecting straps 61 which extend between the interrupted portions of score lines 55, 56. The cut lines 40, 57 define projections 62, 63 at the opposite sides of the top wall 58.

An interrupted score line 64 extends transversely of the blank 17 intermediate the cut lines 41, 42. The spacing between the score line 44 and the score line 64 corresponds generally to the spacing between the score line 36 and the score line 47 and the spacing between the score line 38 and the score line 55. A second interrupted score line 65 is disposed adjacent to and parallel to the score line 64. A generally C-shaped cut line 66 serves as the interruption to the score lines 64, 65, with a major portion of the cut line 66 lying along the score line 65.

An intermediate top wall 67 has the side edges thereof defined by the score line 44 and the cut line 45 along one edge, and by the score line 64 and the cut line 66 along the opposite edge. The score line 65 and the intermediate portion of the cut line 66 also defines an outer partial flange 68. The top wall 67 is connected to the rear wall 32 by connecting straps 69 which are disposed intermediate adjacent portions of the score lines 43, 44. The flange 68 is connected to the top wall 67 by connecting straps 70 which are disposed between adjacent portions of the score lines 64, 65. The cut line 45 defines a projection 71 along one edges of the top wall 67 and the cut line 66 defines a projection 72 along the opposite edge of the top wall 67.

In the use of the can holder 14, while the blank 17 is still in its flat state, the three cans 11, 12 and 13 which are to be combined into the package 10, are set on the base 27 in alignment with each other and the base 27. The flange 24 and the rear wall 32 are then swung upwardly to vertical positions, such as is shown in FIGURE 1. The upward folding of the flange 24 results in the formation of openings 73 in the lower edge of the flange 24 coextensive with the projections 33 of the base 27. The adjacent portions of the lower beads 15 of the cans 11, 12 and 13 project through the openings 73 and the flange 24 interlocks over the lower beads 15 to prevent upward movement of the cans 11, 12 and 13.

When the rear wall 32 is swung upwardly to its vertical position, openings 74 are formed in the lower edge thereof, which openings are coextensive with the projections 34 and into which the lower beads 15 of the cans 11, 12 and 13 project in the manner generally illustrated in FIGURE 2 to further interlock the lower portions of the cans 11, 12 and 13 with the can holder 14 to prevent upward movement of the cans.

The top walls 46, 58 and 67 are then swung over the upper ends of the cans 11, 12 and 13, and the partial flanges 50, 59 and 68 are swung downwardly into alignment with the continuous flange 24, as is best shown in FIGURE 1. When the top wall 46 is swung in place

overlying the can 11, an opening 75 is formed at the upper edge of the rear wall 32 in alignment with the projection 53 and the upper bead 16 of the can 11 projects through the opening 75 and overlies the upper edge of the rear wall 32 to form an interlock therewith. A similar opening will be formed coextensive with the projection 62 when the top wall 58 is swung into overlying relation with respect to the can 13. This latter opening is referred to by the numeral 76 and is illustrated in FIGURE 3.

When the top wall 67 is swung into overlying relation with respect to the can 12, an opening 77 is formed at the upper edge of the rear wall 32 in alignment with the projection 71. The top bead 16 of the can 12 projects through the opening 77 and the rear wall 32 is interlocked beneath the top bead 16 of the can 12.

When the flanges 50, 59 and 68 are moved into their vertical positions to complete the formation of the package 10, similar openings to those described above will be formed in alignment with the projections 54, 63 and 72. The opening aligned with the projection 54 is referred to by the numeral 78 and receives the top bead 16 of the can 11. The opening aligned with the projection 72 is referred to by the numeral 79 and receives the top bead 16 of the can 12. Similarly, the opening aligned with the projection 63 is referred to by the numeral 80 and receives the top bead of the can 13. The flanges 50, 59 and 68 are locked beneath the top beads of their respective cans and prevent relative downward movement thereof.

It is to be understood that when the cans 11, 12 and 13 are snapped into place within the can holder 14, the interlock between the cans and the can holder becomes a very firm one due to the relative dimensions of the cans and the can holder. As a result, a very rigid package 10 is formed, which package is tightened by any tendency of the cans to move relative to each other and to the can holder 14. The interlock between the cans and the can holder is such that it is necessary to at least in part tear the can holder in order to remove one of the cans. When the cans 11, 12 and 13 are engaged within the can holder 14, the various connecting straps 26, 31, 52, 53, 60, 61, 69 and 70 assume diagonal positions, as is best shown in FIGURES 1, 2, and thus provide the desired interlock.

At this time, attention is directed to the fact that each of the cans 11, 12 and 13 is readily accessible and may be removed from the holder 14 without disturbing the other cans. For example, when the can 13 is to be removed, the flange 59 is pulled outwardly and upwardly to clear the associated portion of the top bead 16 of the can 13. The top wall 58 is then free for upward swinging movement to completely release the top bead 16. The can 13 may then be readily manipulated to release the lower bead 15 thereof. The package 10 with the can 13 removed is shown in FIGURE 2.

From the foregoing, it will be readily apparent that the can holder 14 is particularly adapted to receive two cans of the same height and a third can of a different height, with the two similar cans being disposed at the opposite ends of the can holder. Not only does the can holder provide for a rigid package, but also provides for suitable space for ornamentation either of a descriptive nature or a sales appeal nature. In addition, the front portions of the cans are left exposed so that the labels thereof may be easily read, thus adding to the attractiveness of the completed package.

From the foregoing, it will be seen that novel and advantageous provision has been made for carrying out the desired end. However, attention is directed to the fact that variations may be made in the example structure disclosed herein without departing from the spirit and scope of the invention, as defined in the appended claims.

I claim:

1. A holder for cans and the like having beaded ends wherein the cans are arranged in a row and at least one

of the cans is of a different height from the others, said holder comprising an elongated base having side edges and ends, a rear wall extending upwardly from said base along one of said side edges, a plurality of top walls connected to said rear wall along the upper edge thereof and projecting into overlying relation to said base, said top walls being spaced from said base different distances, a continuous flange extending upwardly from said base along the other of said side edges, and individual flanges extending downwardly from said top walls remote from said rear wall and in widely spaced aligned relation with respect to said continuous flange, said holder having aligned lower bead receiving openings therein at the intersections of said base with said continuous flange and said rear wall and aligned upper beading receiving opening therein at the intersections of said top walls with said rear wall and said individual flanges.

2. The holder of claim 1 wherein two of said top walls of like spacing from said base are separated by one of said top walls of a different spacing from said base.

3. The holder of claim 1 wherein said base is separated from and connected to said rear wall and said continuous flange by lower intermediate portions defined by interrupted pairs of score lines, each of said top walls is separated from and connected to said rear wall and said individual flanges by upper intermediate portions defined by another interrupted pair of spaced score lines, said bead receiving openings being formed in said intermediate portions by cuts connecting adjacent portions of said score lines, said cuts defining locking portions on said rear wall and said continuous and individual flanges for snapping engagement behind the beads of the cans to lock cans within the holder.

4. The holder of claim 1 wherein said base is separated from and connected to said rear wall and said continuous flange by lower intermediate portions defined by interrupted pairs of score lines, each of said top walls is separated from and connected to said rear wall and said individual flanges by upper intermediate portions defined by another interrupted pair of spaced score lines, said bead receiving openings being formed in said intermediate portions by cuts connecting adjacent portions of said score lines and said intermediate portions being diagonally disposed.

5. The holder of claim 1 wherein said base is separated from and connected to said rear wall and said continuous flange by lower intermediate portions defined by interrupted pairs of score lines, each of said top walls is separated from and connected to said rear wall and said individual flanges by upper intermediate portions defined by another interrupted pair of spaced score lines, said bead receiving openings being formed in said intermediate portions by cuts connecting adjacent portions of said score lines, said cuts defining can bead engageable projections on said base and said top wall in alignment with said openings.

6. The holder of claim 1 wherein said base is separated from and connected to said rear wall and said continuous flange by lower intermediate portions defined by interrupted pairs of score lines, each of said top walls is separated from and connected to said rear wall and said individual flanges by upper intermediate portions defined by another interrupted pair of spaced score lines, said bead receiving openings being formed in said intermediate portions by cuts connecting adjacent portions of said score lines, said cuts defining locking portions on said rear wall and said continuous and individual flanges for snapping engagement behind the beads of the cans to lock cans within the holder, said cuts also defining can bead engageable projections on said base and said top wall in alignment with said openings.

7. A package comprising at least two upper and lower beaded containers of different heights and a holder engaging around said containers and holding said containers in alignment, said holder including a generally rectangular base underlying said container, said base having

side edges and ends, a rear wall extending upwardly from said base along one of said side edges, a continuous flange extending upwardly from said base along the other of said side edges, said rear wall and said continuous flange being interlocked with said containers' lower beads, a top wall for each of said containers extending from said rear wall into overlying relation to said containers and said base, each of said top walls being spaced from said base in accordance with the height of its respective container, and an individual flange depending from each top wall in widely spaced aligned relation with respect to said continuous flange, said rear wall and said individual flanges being interlocked with said containers' upper beads.

8. A package comprising three rigid containers in a row, the outer ones of said containers being of like height and the central one of said containers being of a different height, and a C-shaped vertical cross-sectional holder engaging around and separately holding each of said containers in alignment with the others and for individual removal, said holder having a separate top wall for each container.

9. A package comprising three containers in a row, the outer ones of said containers being of like height and the central one of said containers being of a different height, and a holder engaging around and separately holding each of said containers in alignment with the others and for individual removal, said containers having upper and lower beads, said holder including a generally rectangular base underlying said container, said base having side edges and ends, a rear wall extending upwardly from said base along one of said side edges, a continuous flange extending upwardly from said base along the other of said side edges, said rear wall and said continuous flange being interlocked with said containers' lower beads, a top wall for each of said containers extending from said rear wall into overlying relation to said containers and said base, each of said top walls being spaced from said base in accordance with the height of its respective container, and an individual flange depending from each top wall in widely spaced aligned relation with respect to said continuous flange, said rear wall and said individual flanges being interlocked with said containers' upper beads.

10. A blank for forming a holder for a plurality of beaded containers of different heights, said blank being generally rectangular in outline and having side edges and ends, a first set of interrupted score lines extending between said blank side edges adjacent one end, generally C-shaped cuts extending between said score lines and combining with said first set of score lines to define a flange at said blank one end, a second set of interrupted score lines extending between said blank side edges generally parallel to said first set of score lines, generally C-shaped cuts extending between said score lines and cuts to define a base panel, a rear wall defining panel disposed adjacent to said base panel and separated therefrom by said second set of score lines and cuts, partial outer interrupted score lines and cuts extending inwardly from the side edges of the blank in aligned relation and generally parallel to said blank ends, an intermediate partial score line and cut arrangement disposed intermediate said outer score lines and cuts and in offset relation thereto, said outer and intermediate partial score lines and cuts separating said rear wall panel from top wall panels disposed adjacent the other end of the blank, parallel cut lines extending inwardly from the other end of the blank in alignment with the ends of the inter-

mediate partial score line and cut arrangement and terminating at said rear wall panel defining three separate top wall panels, and a score line and cut arrangement defining a flange at the other end of the blank along each top wall panel.

5 11. A holder for cans and the like having beaded ends wherein the cans are arranged in a row, said holder being C-shaped in vertical section and comprising an elongated base having side edges and ends, a rear wall extending upwardly from said base along one of said side edges, a plurality of top walls connected to said rear wall along the upper edge thereof and projecting into overlying relation to said base, a continuous flange extending upwardly from said base along the other of said side edges, and individual flanges extending downwardly from said top walls remote from said rear wall in widely spaced aligned relation with respect to said continuous flange, said holder having aligned lower bead receiving openings therein at the intersections of said base with said continuous flange and said rear wall and aligned upper beading receiving opening therein at the intersections of said top walls with said rear wall and said individual flanges.

10 12. A package comprising three rigid containers disposed in a row, the outer ones of said containers being of like height and the central one of said containers being of a greater height, and a C-shaped vertical cross-sectional holder engaging around and separately holding said containers in alignment and for individual removal, said holder having a separate top wall for each container.

15 13. A blank for a can holder comprising a generally rectangular sheet, a first set of interrupted score lines and spaced cuts extending transversely across the sheet adjacent one end and setting out a continuous flange portion, a second set of interrupted score lines and together with the first set of score lines and spaced cuts defining a base portion, said first set of score lines and spaced cuts defining transversely spaced connecting straps connecting said base portion to said continuous flange portion, a rear wall portion disposed adjacent said base portion; said second set of score lines and spaced cuts defining transversely spaced connecting straps connecting said rear wall portion to said base portion, longitudinal cut lines extending along the third points of the width of the sheet from the other edge of said sheet to said rear wall portion, and in part defining a plurality of top wall portions having connected partial flange portions, a partial interrupted score line and cut line set separating each of said top wall portions from said rear wall portion and the respectively partial flange portion of the top wall portion, each of said partial interrupted score lines and cut line sets defining spaced connecting straps.
